United States Patent Office

Des. 217,438
Patented May 5, 1970

217,438

JAR OR THE LIKE

Sara L. Balbach, Corning, Richard W. Greger, Elmira, and Allen J. Samuels, Corning, N.Y., assignors to Corning Glass Works, Corning, N.Y., a corporation of New York

Continuation-in-part of design applications, Ser. No. 10,692, and Ser. No. 10,698, both Feb. 23, 1968. This application Dec. 10, 1968, Ser. No. 14,862

Term of patent 14 years

Int. Cl. D9—01

U.S. Cl. D9—154

Fig. 2

Fig. 1

Fig. 3

FIG. 1 is a top plan view of a jar or the like embodying our new design.

FIG. 2 is a side elevational view.

FIG. 3 is an enlarged fragmental elevational view partially in section.

This application is a continuation in part of our earlier copending applications Ser. No. D.10,692 and D.10,698, both filed Feb. 23, 1968, and now abandoned.

We claim:

The ornamental design for a jar or the like, as shown and described.
